UNITED STATES PATENT OFFICE.

CORNELIUS W. SMITH, OF EAST ORANGE, NEW JERSEY, ASSIGNOR OF ONE-THIRD TO GEORGE CAMPBELL, OF EAST ORANGE, NEW JERSEY, AND ONE-THIRD TO EDWIN SMITH, OF HARRISON, NEW JERSEY.

SIGNAL-LANTERN.

SPECIFICATION forming part of Letters Patent No. 795,238, dated July 18, 1905.

Application filed March 1, 1905. Serial No. 247,984.

To all whom it may concern:

Be it known that I, CORNELIUS W. SMITH, a citizen of the United States of America, and a resident of East Orange, county of Essex, 5 and State of New Jersey, have invented certain new and useful Improvements in Signal-Lanterns, of which the following is a specification.

My invention relates generally to signal-lanterns which are constructed to give alternately different colored lights from one and the same structure; and, more specifically, it consists of an improved attachment for producing such variation of color in the light, which 15 may be conveniently applied to the standard form of railway signal-lanterns now in use.

It is obvious, of course, that if one and the same lantern can be indifferently used to produce a red and a white light or a green and a 20 white light the number of lanterns necessary for railroad companies to purchase and maintain and for the brakeman to carry will be reduced one-half. It has heretofore been attempted to produce lanterns which could be 25 arranged to give out different colored lights, according to the adjustment of the apparatus; but such lanterns have been complicated and costly in construction, and it has been impossible to apply the improvement to the many 30 thousands of railway signal-lanterns already in use.

My invention produces a simple and inexpensive apparatus for bringing about the desired result above set forth, and the device may 35 be applied to the standard railway signal-lanterns now in use without removing or modifying any of the parts thereof, but by simply adding a simple and inexpensive attachment.

The preferred form of apparatus embodying my invention is illustrated in the accompanying two sheets of drawings, in which—

Figure 1 is a vertical central section of the standard railway-lantern with my invention applied thereto, the movable parts of the attachment being shown in one position in full lines and in another position in dotted lines. Fig. 2 is a vertical central section at right angles to the plane of Fig. 1, showing the lan-

tern-top swung to one side and the movable glass cylinder in a lifted position. Fig. 3 is 50 a detail of the apparatus for attaching the supporting device to the movable glass cylinder.

Throughout the drawings like reference-figures indicate like parts. 55

1 represents the standard railway-lantern, in which is contained the lamp-body or oil-reservoir 2, provided with any usual form of burner producing a flame 3.

4 is the ordinary swinging top for the lantern, hinged at 5 to the main frame.

6 is a movable cylinder of colored glass, usually red, which is supported by the bail-wire 7. Preferably this cylinder 6 has its upper edges 6^a bent inwardly for a purpose 65 hereinafter to be explained. This bail-wire may be attached to the cylinder in any convenient manner; but I prefer the metal clips 8, (shown in detail in Fig. 3,) which have their upper and lower portions bent over to 70 form hooks, as shown at 8^a and 8^b. The bail-wire 7 is connected to a central wire 9, preferably formed by twisting two portions of wire together so as to form a loop 10 at the upper end and another loop 10^a at the lower end. 75 The bail-wire 7 is inserted through the lower loop 10^a, and any convenient form of ring 11 may be inserted through the upper loop 10.

12 is a spring-catch or friction device, which normally engages the central wire 9 and by 80 projecting into the spaces left between the twisted strands of said wire serves to hold it in any position of adjustment. This spring-dog 12, as shown, is riveted to the lantern-top at 13 and may be withdrawn from engagement with 85 the signal-wire 10 by means of the projecting lug or tailpiece 14, to which the thumb of the operator may be applied.

Preferably I provide a sleeve 15, fastened to the lantern-top 4 to guide and steady the 90 central supporting-wire 9.

Such being the construction of my invention, its operation is as follows: Taking the standard lantern shown in the drawings, I insert the guiding-sleeve 15 in the lantern-top 4, 95 together with the central supporting-wire 9,

and fasten the same in place by expanding the ends of said sleeve 15, as shown, or in any other convenient manner. The spring-dog or friction device 12 is then applied to the lantern-top. The clips 8 are attached to the glass cylinder 6 by bending over the ends of said clips, as shown at 8^a and 8^b in Fig. 3. The bail-wire 7 is then inserted through the loop 10^a at the lower end of the central supporting-wire and its ends are bent around into engagement with the loops 16 left in the upper ends of the clips 8. This leaves the parts in the position shown in Fig. 2. When the lantern-top is swung down into the normal position, the parts are brought into the position shown in full lines in Fig. 1. In such position the lantern gives the usual white light when it is lighted. If it is desired to signal with the red light, the operator merely seizes the ring 11 and pulls the parts up into the position shown in dotted lines in Fig. 1. It is then evident that all the light-rays which can escape under the lower skirt of the lantern-top must pass through the colored glass of the cylinder 6, as indicated by the broken lines 20 20 in Fig. 1. The purpose of the inwardly-bent edges 6^a of the colored-glass cylinder 6 is to secure this intercepting of all the escaping rays of light by the colored-glass cylinder when in raised position without extending the amplitude of vertical motion of said colored-glass cylinder. It is evident that the diameter of the glass cylinder and its limit of vertical motion are fixed by the proportions of the standard lantern shown in the drawings. It is also evident that if the glass cylinder 6 were continued up in a straight line without its upper edges being bent inwardly it would not intercept all the light-rays, even in its highest position, supposing that its height were the same as here shown. It is obviously impossible to increase the height of the movable glass cylinder without having its upper edges intercept a portion of the light-rays when the glass is in its lowermost position. By bending inwardly the upper edges of the glass cylinder I am enabled to solve this difficulty and to intercept all of the light-rays when the glass cylinder is in its highest position, to intercept none of them when the cylinder is in its lowest position, and to secure these results with the limited amount of motion possible in the standard lantern construction.

55 Referring to the above-described method of assembling the parts, of course this may be varied and the glass cylinder, bail-wire, and the central supporting-wire assembled and all inserted in the lantern at once by pushing the central wire up through the guiding-sleeve and afterward attaching the lifting-ring 11. It is evident that in the case of breakage or getting out of adjustment of any of the parts the same may be easily removed by reversing

the series of steps by which they were introduced into the lamp.

The advantages of my invention comprise its simplicity and small cost, the ease with which it may be attached to the lanterns now in use, its complete changing of the character of the light given off by the lantern without modifying in any detail the parts of the lantern as now made, and the ease with which all parts may be removed for replacement or repair. It is evident, of course, that various changes could be made in the details of the apparatus shown in the drawings without departing from the spirit and scope of my invention. Other forms of supporting and attaching wires might be employed, other means for frictionally supporting the parts in their adjusted position might be substituted, the guiding-sleeve 15 might be dispensed with, or other guiding means substituted. These and similar changes in construction I should consider mere mechanical modifications of my invention and still within the limits thereof.

In order that the full supply of air necessary to maintain the flame may be supplied to the burner when the lantern is swung violently, I provide means for admitting air to the inside of cylinder 6 below burner producing the flame 3. Preferably I provide openings 21 21 in the bottom of the lantern, which extend inside of the cylinder 6.

Having therefore described my invention, what I claim as new, and desire to protect by Letters Patent, is—

1. In a lantern, the combination of a movable cylinder of colored glass adapted to fit down about the lamp-body or to be raised about the flame, a vertically-movable plunger extending down through the lantern-top, a guiding-sleeve fixed inside the lantern-top in which said plunger moves, means for suspending the cylinder of colored glass from said plunger and a yielding device for holding the plunger and cylinder in their elevated positions of adjustment.

2. In a lantern provided with a swinging top the combination of a movable cylinder of colored glass adapted to fit down about the lamp-body or to be raised about the flame, and means for moving said cylinder of glass extending downward through the swinging lantern-top, said supporting means comprising a wire extending centrally through the lantern-top, and a bail-wire loosely jointed to the lower end of the central wire and connected to the glass cylinder at either side.

3. In a lantern the combination of a movable cylinder of colored glass adapted to fit down about the lamp-body or to be raised about the flame, and means for moving said cylinder of glass extending downward through the lantern-top, said supporting means comprising a wire extending centrally through the lantern-top, and a bail-wire jointed to the

lower end of the central wire and connected to the glass cylinder at either side, a guiding-sleeve set in the lantern-top for said central wire, and a friction device for holding the central wire in any position of adjustment.

4. In a lantern provided with a hinged top, the combination of a movable cylinder of colored glass adapted to fit down about the lamp-body, or to be raised about the flame, and means for moving said cylinder of glass extending downward through the hinged top, said supporting means comprising a wire ex-

tending centrally through the hinged lantern-top, and a bail-wire loosely jointed to the lower end of the central wire and connected to the glass cylinder at either side by clips embracing the glass ring. 15

Signed at New York, N. Y., this 28th day of January, 1905.

CORNELIUS W. SMITH.
